UNITED STATES PATENT OFFICE.

PAUL KLEMOFF, OF CHICAGO, ILLINOIS, ASSIGNOR TO GENERAL AMERICAN TANK CAR CORPORATION, OF CHICAGO, ILLINOIS, A CORPORATION OF WEST VIRGINIA.

CAR UNDERFRAME.

Application filed October 10, 1924. Serial No. 742,864.

My improvement relates more particularly to body-bolster construction of underframes especially for tank cars.

The particular type of underframe to which my invention relates, as to one of its phases, comprises a center-sill structure with bolster-members secured thereto to extend outwardly therefrom, with the connections between the bolster-members and the center-sill and the form of the bolster-members, such as to cause the structure to present the desired resistance to the stresses to which a structure in use, especially when it forms a part of a tank-car, is subjected, without requiring a cross-connecting member, separate from the bolster-members and extending along the lower portions of the latter for connecting these members either with each other or with the center-sill.

One of my objects is to provide a structure of the general type above referred to, which while being sufficiently resistant to the stresses to which it is subjected in use, may be manufactured at less cost and be of less weight than structures of this type as hitherto designed and by the provision of which manufacturing difficulties will be minimized.

Another object is to provide improvements in the tank-band and running-board attachments of underframes, especially for tank cars, whereby this part of the structure may be produced more economically, and without sacrificing strength of the structure.

Referring to the accompanying drawings:

Figure 1 is a cross-sectional view of a tank car embodying my invention, my improved body-bolster construction being shown in elevation and a portion of the tank being broken away. Figure 2 is a broken sectional elevational view taken at the line 2 on Fig. 1 and viewed in the direction of the arrow. Figure 3 is a broken plan view of the structure, with the tank and certain of the saddle blocks, forming a part of the structure, removed. Figure 4 is a section taken at the line 4—4 on Fig. 1 and viewed in the direction of the arrows, with portions of the spacer shown in section and Figure 5, a section taken at the line 5 on Fig. 1 and viewed in the direction of the arrow.

The construction of underframe illustrated in the drawings is formed of a center sill comprising two parallel, spaced-apart, channel girders 10, the upper and lower

flange portions 11 and 12 of which extend outwardly, as shown, whereby the channel portions of the sill, and represented at 13, toe outwardly. The girders 10 are connected together at their upper edges by a cover-plate 14 which overlies the flanges 11 throughout the length of the sill and is secured thereto by rivets 15. The girders 10 are also connected together, in the plane of each body bolster portion of the structure, by a center-brace member 16 secured to the girders by rivets 17, and extending across the underside of the sill and across the member 16, at each body bolster, is a center-plate member 18 which is secured to the girders 10 by rivets 19 and to the member 16 by rivets 20.

Each body bolster portion of the car comprises two members 21, which are preferably cast steel members, which extend cross-wise to the sill and outwardly therefrom in opposite directions. The members 21 are of the same construction, each being so shaped as to be fitted at one end into the adjacent channel 13, as shown. Each member 21 is formed with a central web 22 apertured at 23 and 24 and presenting therebetween a web-portion 25 which inclines downwardly and outwardly as shown. Each member 21 is provided at opposite faces thereof with flanges 26, 27, 28 and 29 which extend along the upper and side marginal edges of the member and along its lower portion, respectively. The member 21 below the flanges 29 at the lower portion of the member 21 at its inner end, has integrally formed therewith a web 30 provided along its side and bottom edges, with flanges 31, 32 and 33. The marginal edges of the openings 23 and 24 are provided with flanges 34 and 35, respectively, as shown, the flanges 34 merging at their ends into the flanges 29. The flanges 26, 27 and 28 in the construction shown, are of substantially uniform width and relatively wide, whereas the flanges 34 and 35 and the flanges 32 and 33 are relatively narrow, as shown. The vertical portions of the flanges 31 are of the same width as the vertical flanges 28 of which they are continuations and the flanges 29 are of slightly less width than the flanges 26, 27 and 28.

The bolster members 21 extend flatwise at their flanges 28 and 31 and portions of their flanges 26 against the side and upper walls of the channels 13 and are secured to 110

the center sill in this position by the rivets 15 and 17, which extend through the flanges 26, 28 and 31, and by rivets 36, and additional connection between the members 21 and the 5 center sill structure is provided by the provision of a plate 37 which extends cross-wise of the center sill and across the plate 14 to a position in which its opposite ends overlap the upper surfaces of the members 21, 10 this plate being secured to the center sill by the rivets 15 and rivets 39 and to the members 21 by rivets 40, 41 and 42.

The body bolster constructions described, in the particular construction shown, form 15 saddles for supporting the tank, represented at 43, there being provided between the members 21 and the tank 43, a series of filler, or saddles, blocks 44 of any suitable material as 20 for example wood, such as are commonly provided.

The upper surfaces of the bolster members 21 are shown of concave form to conform 25 generally to the curvature of the tank, though it will be understood that under certain conditions the upper surfaces of these members may be varied, as desired, in some cases being made straight.

Each bolster member 21 is provided, adjacent its outer end, with depending pressed 30 steel body side bearings 45 secured thereto by the rivets represented at 46, and at its outer extremity with an outwardly projecting lug 47 cast integrally with the member 21 and of channel form as shown with its 35 side flanges 48 and 49 extending upwardly from its base-portion 50. The lugs 47 form supports for running-board-supporting members 52 and tank-bands 53. The running-board-supporting members 52 are 40 of angle form in cross-section, as shown in Fig. 2, and fit flatwise, at their flange-portions 54, against the side surfaces of the flanges 48 in which position they are secured by rivets 55 and 56, the members 52 being 45 shown as reinforced by angle-bars 57 secured thereto by the rivets 56 and rivets 58. The members 52 preferably bear endwise against the outer end-faces of the members 21 and, by preference, are of the general shape 50 shown; namely, of outwardly tapering form, at their inner ends, as represented at 59, with their extreme outer ends, at which the running-boards 60 are secured, relatively shallow. The members 52 thus shaped are 55 sufficiently strong to resist the stresses exerted against them in use, while being of relatively light weight, with consequent economy of manufacture.

The ends of the tank-bands 53, a pair of 60 which is provided for the tank at each bolster portion, extend downwardly through holes in the sub-portion 50 of the lug 47 and are provided at their lower, protruding, threaded ends with nuts 61 for drawing the 65 bands about the tank.

Each member 21 is also provided with push-pole pockets 62 integral therewith, and with a lug 63 at the opening 24 for receiving a U-bolt 64 provided for the purpose of clamping the air-line brake-pipe (not 70 shown) in place.

By providing the members 21 in the form shown and described, and particularly when assembled with the other parts, as shown, they may be of relatively light weight, and 75 economically manufactured and still present the necessary resistance to the forces exerted against them in the use of the car, without requiring the use of cross-members at the lower portions of the members 21 directly 80 connecting them either with each other or with the sill of the car. In this connection the provision of the inclined stress-resisting elements 25, especially in connection with the flanging of the members, including the 85 flanges 29, is of especial advantage as by thus disposing the elements 25 they occupy positions in which they resist stresses to the best advantage with the minimum cross-section of metal. Furthermore by forming the 90 members 21, as shown, the bearing of these members against both the upper and lower flanges of the sill-girders is rendered unnecessary and thus grinding or otherwise shaping the preformed members 21 to fit them 95 in the channels of the girders, when variations in the latter occur, is unnecessary.

While I have illustrated and described a particular construction embodying my invention, I do not wish to be understood as 100 intending to limit it thereto as the same may be variously modified and altered without departing from the spirit of my invention.

What I claim as new and desire to secure 105 by Letters Patent, is:

1. A car underframe comprising a center-sill structure, bolster-members located at opposite sides of said center-sill and extending outwardly therefrom, said members being provided with webs and flanges extending crosswise thereof, each of said webs containing a plurality of openings therethrough so shaped as to cause each web to present a stress-resisting portion which inclines downwardly in a direction away from said center-sill, certain of said flanges being provided along the marginal edges of said apertures, and means connecting said members to said center-sill. 110

2. A car underframe comprising a center-sill structure, bolster-members located at opposite sides of said center-sill and extending outwardly therefrom, said members being provided with webs containing apertures and provided with flanges along their lateral and top marginal edges and along their lower portions, said flanges at the lower portions of said members being substantially straight and connected with the 115 120 125 130

flanges at the sides of said members, said members also being provided with depending flanged web portions which extend below the said flanges at the lower portions of 5 said members and the flanges of which form continuations of the flanges at the inner ends of said members, said apertures being so disposed as to cause each web to present a stress-resisting portion which inclines 10 downwardly in a direction away from said center-sill, and means connecting said members to said center-sill.

3. A car underframe comprising a center-sill structure presenting channel portions toeing outwardly, bolster-members located at opposite sides of said center-sill and extending outwardly therefrom, said members extending at their inner ends into said channels and each presenting a stress-resisting portion which inclines downwardly 20 in a direction away from said center-sill, said members being provided with flanges at their side and top marginal edges and along their lower portions and extending 25 into said channels at flanged portions thereof, said members also being provided with depending flanged portions extending below said first-referred-to flanges and also extending 30 into said channels, and means securing said members to said center-sill and engaging the flanges at the inner ends of said members.

4. A car underframe comprising a center-sill structure, bolster-forming members carried thereby and extending outwardly therefrom, lugs on said members presenting upwardly-extending surfaces and containing tank-band-receiving openings, running-board-supporting members positioned flatwise against the outer vertical surfaces of 40 said lugs, and means securing said supporting members in said position.

5. A car underframe comprising a center-sill structure, bolster-forming members car-

ried thereby and extending outwardly therefrom, lugs on said members presenting upwardly-extending surfaces, running-board-supporting members positioned flatwise against said surfaces of said lugs, the inner end portion of each of said last-named members 45 tapered toward the outer end portion, and means securing said supporting members in said position.

6. A car underframe comprising a center-sill structure, bolster-forming members carried thereby and extending outwardly therefrom, lugs on said members presenting upwardly-extending surfaces, running-board-supporting members positioned flatwise 50 against said surfaces of said lugs, the inner end portion of each of said last-named members tapered toward the outer end portion, and means securing said supporting members in said position, the inner extremities 55 of said last-named members endwise abutting the outer end surfaces of said bolster-forming members.

7. A car underframe comprising a center-sill structure, bolster-forming members carried thereby and extending outwardly therefrom, lugs on said members presenting upwardly-extending surfaces, running-board 60 supporting members of angle shape in cross-section positioned flatwise against said surfaces of said lugs, and means securing said 65 supporting members in said position.

8. A car underframe comprising a center-sill structure, bolster-forming members carried thereby and extending outwardly therefrom, channel lugs on said members with 70 their flanges extending upwardly, said lugs containing tank-band-receiving openings, running-board-supporting members positioned flatwise against the outer vertical surfaces of the side flanges of said lugs, and means securing said supporting members in 75 said position.

PAUL KLEMOFF.
